COMBINED BOTTLE AND CAP THEREFOR

Burt S. Avedon, Boston, and Richard A. Hussey, Watertown, Mass., assignors to The Gillette Company, Boston, Mass.

Filed Dec. 10, 1970, Ser. No. 26,386

Term of patent 14 years

Int. Cl. D9—01

U.S. Cl. D9—168

Fig. 1

Fig. 2

Fig. 3

Fig. 4

Fig. 5

FIG. 1 is a front elevational view of a combined bottle and cap therefor showing my new design;

FIG. 2 is a side elevational view thereof;

FIG. 3 is a back elevational view thereof;

FIG. 4 is a top plan view thereof; and

FIG. 5 is a bottom plan view thereof.

The undisclosed side is substantially a mirror image of the side shown.

We claim:

The ornamental design for a combined bottle and cap therefor, substantially as shown and described.
